and, according to the best authorities, is a plant of
Europe and North America, introduced into England
in the reign of King Edward III. It is a small shrub
and bears the name of a "small shrub" or "small
bush." It is a native of Europe and America, and
is found in the United States, particularly in the
Atlantic coast states, and in the West Indies.

UNITED STATES PATENT OFFICE

2,497,118

APPARATUS FOR LIFTING CYLINDRICAL OBJECTS

**John J. Ferrario and Joseph Dondero,
San Francisco, Calif.**

Application May 20, 1947, Serial No. 749,312

9 Claims. (Cl. 214—66)

1

ly facing curved or arcuate inner surfaces 12 may

The present invention relates to articles lifting devices, and is more particularly directed to devices for lifting and firmly holding cylindrical objects, such as paper rolls for newsprint, pipe and the like.

An object of the invention is to provide an improved apparatus for holding, lifting and tilting heavy cylindrical objects. Such apparatus is attachable to an industrial truck to enable conveyance of the cylindrical objects along the floor of a dock, warehouse or other establishment.

Another object of the invention is to provide an apparatus capable of clamping on to a cylindrical object, lifting such object and tilting it through a substantial angle, as between horizontal and vertical positions.

Still another object of the invention is to provide an apparatus capable of simultaneously clamping on to a plurality of cylindrical objects, lifting such objects from the ground, floor or other support, and tilting them through a substantial angle.

A further object of the invention is to provide an hydraulically actuable device for lifting and tilting heavy cylindrical objects, which device is relatively easy to control and capable of comparatively rapid operation.

One form which the invention may assume is exemplified in the following description and illustrated by way of example in the accompanying drawings in which:

Fig. 1 is a front elevation of an apparatus for handling a plurality of cylindrical objects, such as rolls of newsprint paper.

Fig. 2 is a side elevation of the apparatus disclosed in Fig. 1.

Fig. 3 is a top plan view on an enlarged scale of one half of the apparatus illustrated in Fig. 1.

Fig. 4 is a longitudinal view, partly in section and partly in elevation, showing primarily the tilting mechanism and the main frame or support.

Fig. 5 is a diagram of the hydraulic system for controlling and operating the apparatus.

The embodiment of apparatus specifically illustrated in the drawings has been designed primarily for the handling of large, heavy rolls of paper used in newspaper plants. Although specific reference will be made in this specification to the handling of newsprint paper, it is to be understood that the apparatus is capable of handling other cylindrical objects, and, in its broader sense objects of various forms.

The rolls of paper 10 are adapted to be clamped to a transverse tiltable frame 11, whose opposite-

ly facing curved or arcuate inner surfaces 12 may receive the rolls. A curved supporting plate 13 is welded or otherwise secured to each inner arcuate surface 12 of the frame, against which a paper roll is to be urged. In effect, these curved plates 13 converge downwardly toward each other toward a narrow lower adjoining edge 14, which may be curved.

10 may be curved. A movable curved clamping jaw 15 is disposed at each side of the transverse frame 11 and is adapted to engage the opposite side of the curved surface of the cylindrical roll of paper 10 to force it against the supporting plate 13, whereby the paper is clamped to the frame. This curved 15 jaw has a generally concave or arcuate inner surface 16 and a pair of spaced lugs or ears 17, through the medial portion of which extends a pivot bolt 18, passing through the lower end of a lever 19 disposed between the lugs. The lever 20 is pivotally mounted on a bolt 20 extending through its medial portion and also through the end of the tiltable frame 11, the upper arm of the lever having bifurcated ends 21 through and between which a pivot pin 22 extends, pivotally 25 receiving the outer end of a piston rod 23 extending into a transversely arranged cylinder 24 located in the upper portion of the tiltable frame. The inner end 25 of the cylinder is swingably mounted upon a pivot bolt 26 secured to the upper 30 portion of the frame 11.

Fluid under pressure is adapted to enter the piston end 25 of the cylinder and also the rod end 27 of the cylinder, in order to move the piston 28 and attached rod 23 transversely of the apparatus, and, because of its pinned connection 22 with the lever 19, swing the movable jaw 15 to and from the stationary curved jaw 13, to clamp a roll of paper 10 to the frame 11 or to unclamp it therefrom. It is apparent that such pivotal movement can occur freely because of the pivotal mounting 26 of the inner end 25 of the cylinder on the frame 11. It is also to be noted that the tendency for gravity to swing the movable jaw 15 about its pivot pin 18 to a horizontal, pendant position is limited by engagement of the back side 15a of the jaw with the lower end 29 of the lever arm 19, which functions as a stop.

The mechanism for clamping each cylindrical roll of paper is the same on both sides of the machine, the device being essentially symmetrical about a longitudinal vertical plane passing through the apparatus, although the parts are arranged in opposed relation. For that reason, the description of one side of the device in this specification will suffice for both sides.

By virtue of a suitable valve mechanism, referred to hereinafter, fluid under pressure simultaneously enters either the rod ends 27 of both cylinders 24 or their head ends 25, to swing the movable jaws 15 simultaneously inwardly or outwardly to clamp two rolls of paper 10 to the supporting frame 11 at the same time, or to unclamp such rolls of paper therefrom.

Assuming that the rolls of paper are resting on their sides adjacent one another upon the floor of a warehouse or dock, the apparatus may be disposed thereover and the pistons 28 moved outwardly to swing the movable jaws 15 inwardly against the rolls of paper 10, forcing them against the inner supporting plates 18, and thus clamping them to the frame 11. Thereafter, the rolls may be lifted by elevating the truck boom 30 of an industrial truck of a known design, to be referred to hereinafter, and, if desired, the rolls may be tilted to a vertical position for placing on their ends.

In order to provide for tilting the transverse frame 11 about a horizontal axis, a pair of opposed side frames 31 are provided, each frame being of generally triangular form and composed of integrated vertical, horizontal and diagonal legs 32, 33, 34. A cross frame member 35 extends between and is secured to the side frames 31. Rearwardly extending brackets 36 are welded, or otherwise suitably secured, to the side frames 31, being secured to the vertical boom 30 of an industrial truck of any suitable type in which the boom is telescopically arranged to permit its substantial elevation, to correspondingly elevate or lower the entire apparatus and any objects that may be carried thereby. In view of the extent of overhang of the frame 31 of the apparatus from the truck boom 30, the former normally tends to remain in engagement with the front of the boom (see Fig. 2).

The transverse tiltable frame 11 has a plurality of rearwardly extending arms 37, 38, 39 welded or otherwise secured to it, such arms including, on each side of the central longitudinal vertical plane of the apparatus, a pair of outer members 37, 38 disposed on opposite sides of a side frame 31 and pivotally mounted upon a fulcrum rod 40 extending through the rear arm bearing bosses 41, 42 and an intervening bearing boss 43 on the forward end of the side frame 31 at the lower juncture of the horizontal and diagonal legs 33, 34. The inner arm 38 is welded to a sleeve or tube 44 extending across the apparatus for attachment to the corresponding boss 42 of the arm 38 on the other side of the apparatus.

The tiltable frame 11 also has an inner arm 39 secured to it on each side of its central vertical plane, which is welded to the sleeve 44 and projects rearwardly thereof to provide a lever of the first class. A disk 45 is mounted upon a central bolt 46 extending through the rear end of the inner arm 39, there being another bolt 47 extending through a selected hole of a plurality of circumferentially arranged holes 48 in the disk and through a hole in the inner arm 39 adjacent the bolt 46. A pivot pin 49 fits within one of the other holes 48 in the disk and through the lower end of a piston rod 50 disposed centrally of the apparatus, the pin 49 extending on the other side of the central longitudinal vertical plane for pivotal attachment to a corresponding disk 45 bolted to a corresponding inner arm 39 on the other side of the machine. As stated above, both sides of the apparatus are symmetri-

cal about its longitudinal vertical plane, the apparatus disclosed in Fig. 3 being duplicated on the other side of the vertical center line.

The entire frame 11 may be tilted about the horizontal axis of the fulcrum rod 40 by means of a hydraulic mechanism, including the piston rod 50 referred to above. This rod extends into an inclined cylinder 51 and has a piston 52 at its upper end. Fluid under pressure may be introduced into the head end 53 of the cylinder to force the piston 52 and its rod 50 downwardly, which will swing the rear ends of the tilt arms 39 downwardly and their outer ends upwardly, to tilt the frame 11 upwardly about the horizontal axis of the fulcrum rod 40, which swinging action will also move the paper rolls 10 from a horizontal position toward a vertical position. Such swinging action can occur without restraint from the apparatus because of the pivotal mounting of the upper end 53 of the cylinder 51 on a fulcrum bolt 54 supported within the ears 55 of brackets 56 welded to the cross member 35 of the stationary frame. As indicated, by introducing pressure into the upper head end 53 of the tilt cylinder 51, the tiltable frame 11 will be swung upwardly about its horizontal axis, and, by relieving the pressure, the load of the tiltable frame 11 and of the paper rolls 10 carried thereby will swing the transverse tiltable frame to a downward position, such as indicated in Fig. 2.

The hydraulic system for controlling the operation of the device is disclosed in Fig. 5. The head ends 25 of the clamping cylinders 24 are connected through tubing 57 to a common tube 35 or line 58 leading to a clamp control valve 59, which communicates with a reservoir 60 through a suitable line 61, 62 and also with a pump 63, which can draw fluid, such as oil, from the reservoir 60 through its intake line 64 and force it under pressure through its discharge line 65 into the valve 59. This clamp valve 59 also may be placed into communication with both rod ends 27 of the cylinders 24 through a suitable line 66 having branches 67 running to such outer cylinder ends.

A tilt valve 68 is also provided for controlling the passage of fluid to and from the tilt cylinder 51. A suitable tubing 69 runs from the head end 53 of the cylinder to the valve 68, from which a line 70 connects to the high pressure pipe 65 leading from the pump 63, another line 71 running to the pipe 62 and the reservoir. Suitable manipulation of this tilt valve 68 determines whether fluid under pressure may enter the tilt cylinder 51 to force its piston 52 and rod 50 downwardly, or whether fluid in such cylinder may bleed to the reservoir 60, permitting the load to be tilted back to a horizontal position.

The clamp valve 59 and tilt valve 68 are of known constructions, the clamp valve being of a type capable of selectively connecting the high pressure end 65 of the pump 63 to the head ends 25 of the clamp cylinders 24, while connecting the other ends 27 of the cylinders to the reservoir 60; or which can simultaneously connect the rod ends 27 of such cylinders to the pump 63, and allow the head ends 25 of the cylinders to bleed back to the reservoir. The tilt valve 68 either may be moved to connect the head end 53 of the tilt cylinder 51 with the pump 63 or connect such cylinder with the reservoir 60. Further details of the valves are unnecessary for an understanding of the present invention, since they are of known construction and operation, and may be purchased on the open market.

The apparatus is connected to the truck boom 38 by means of bolts 72 passing through the brackets 36, and may initially occupy the position disclosed in Fig. 2 or the tilt piston 52 may be moved downwardly to cause the tilt-able frame 11 and the supporting plates 13 and movable jaws 15 carried thereby to swing through approximately 90 degrees to a horizontal position, depending upon the position of the rolls of paper 10 to be moved from one location to another. Assuming that such rolls of paper are lying on their sides in a horizontal position, the industrial truck, with the apparatus arranged in the manner illustrated in full lines in Fig. 2, is moved over the paper rolls and the truck boom 38 lowered until the curved supporting plates 13 rest upon two adjacent rolls of paper. The clamp valve 59 is then suitably manipulated so that fluid under pressure supplied by the pump 63 passes through the branch tubes 57 leading to the inner head ends 25 of the clamp cylinders 24, such pressure forcing the pistons 28 and rods 23 outwardly, and, through the swinging of the lever arms 19, moving the clamp plates 15 inwardly against the rolls of paper 10, firmly clamping them to the tilttable frame 11. There-
20 after, the truck boom 38 may be elevated in a known manner, and the rolls of paper trans-ported to the desired point.

If it is desired to swing such rolls of paper to a vertical position, the tilt valve 68 may be appropriately manipulated to place the line 69 leading to the tilt cylinder in communication with the discharge line 65 of the pump, the fluid under pressure forcing the tilt piston 52 and rod 50 downwardly and swinging the frame 11 about the horizontal axis of the fulcrum rod 40 to a position indicated in dotted lines in Fig. 2, wherein the paper rolls are disposed with their axes vertical. The truck boom 38 may now be lowered, if desired, until the paper rolls rest on their ends upon the floor or ground, whereupon the clamp valve 59 may again be suitably manipulated to connect the discharge line 65 of the pump with the tubing 66, 67 leading to the outer rod ends 27 of the cylinders 24, the inner head ends 25 of the cylinders then being allowed to bleed back to the reservoir 60 through the lines 58, 61, 62. The fluid under pressure may be availed of to move the pistons 28 inwardly toward one another in order to swing the jaws 15 outwardly to their full extent, thus unclamping the rolls of paper and allowing the industrial truck to be backed away from such rolls and the apparatus moved to pick up other rolls or ob-
jects.

The leverage on the tilting arms 39 may be changed by attaching the pin 49 passing through the lower end of the tilt piston rod 50 through one of the other holes 48 in the disks 45 bolted to the rear arms of the tilt levers 39. Location of the pin 49 closer to the axis of the fulcrum rod 40 requires more force to effect a tilting action on the tilttable frame 11 and the objects carried thereby, but the tilting action may occur at a faster rate, because of the shorter travel required of the tilt piston 52.

In the event that the radius of curvature of the clamp surfaces 13 and of the curved jaws 15 is substantially the same as the cylindrical rolls of paper, the unclamping action may be retarded through the creation of a vacuum on the paper as the jaws 15 move outwardly. In order to avoid the formation of such a vacuum, the supporting plates and jaws may be provided

with perforations 18 to allow the entry of air to their inner surfaces and the adjoining outer surfaces of the paper.

From the foregoing specific description of the parts, it is apparent that the apparatus may be used to convey objects, and particularly cylindri-
5 cal objects, from one point to another while they are disposed in a horizontal position, or while they are disposed in a vertical position, and to transfer such objects from a horizontal to a vertical position, or vice versa. The ability to elevate the truck boom 38 to a substantial height or extent, as is well known in the industrial truck art, allows rolls of heavy paper to be moved very
10 readily by the apparatus and truck and to be stacked one upon the other, depending upon the extent to which the truck boom may be ele-vated. In actual use, it has been possible to stack at least two rows of cylindrical paper rolls
15 upon one another, and to remove rolls of paper
20 from the upper row with facility.

The apparatus may be secured as a unit to the boom 38 of an industrial truck very readily, simply through passing the bolts 72 through the brackets 36 and boom. It is, of course, apparent
25 that the apparatus may be attached to any other suitable conveyance and will be capable of being clamped about cylindrical objects which may then be elevated from a supporting surface and tilted
30 between a horizontal and vertical position if de-sired, and conveyed from one location to another.

While we have shown the preferred form of our invention, it is to be understood that various changes may be made in its construction by those
35 skilled in the art without departing from the spirit of the invention as defined in the appended claims.

Having thus described our invention, what we claim and desire to secure by Letters Patent is:

40 1. A device of the character described, includ-ing a tilttable frame having a pair of fixed inner oppositely arranged concave jaws, a pair of movable outer concave jaws, each movable jaw being opposite a fixed jaw, means connected to
45 said movable jaws and mounted on said frame, hydraulically operable means on said frame connected to said means for simultaneously moving said movable jaws to and from said fixed jaws, a supporting frame, means pivotally mounting said
50 tilttable frame on said supporting frame for tilting about a generally horizontal axis, and hydraul-ically operable means on said supporting frame connected to said tilttable frame for swinging said tilttable frame about said axis.

55 2. A device of the character described, includ-ing a tilttable frame having a pair of fixed inner oppositely arranged arcuate jaws, a pair of mov-able outer arcuate jaws, each movable jaw being opposite a fixed jaw, a pair of levers each con-nected to a movable jaw and pivotally mounted
60 on said frame, a pair of oppositely arranged cylin-ders pivotally mounted on said frame, pistons in
65 said cylinders each connected to a lever for simul-taneously swinging said movable jaws to and from
70 said fixed jaws, a supporting frame, means piv-o-tally mounting said tilttable frame on said sup-
porting frame for tilting about a generally hor-
izontal axis, a tilt cylinder pivotally mounted on
said supporting frame, and a piston in said cylin-
der connected to said tilttable frame for swinging
said tilttable frame about said axis.

3. A device of the character defined in claim 2, including a fluid reservoir, a pump connected to
said reservoir, valve means for selectively deter-mining the passage of fluid between said pair of

cylinders and either said pump or reservoir, and valve means for selectively determining the flow of fluid between said tilt cylinder and either said pump or reservoir.

4. A device of the character described comprising a main frame adapted to be mounted on the boom of a lift truck, a second frame revolubly mounted on said main frame for rotation about a horizontal axis, a pair of opposed jaws mounted on said second frame including a movable jaw pivotal toward and away from the other jaw, and hydraulic means for pivoting said second frame about said horizontal axis and for pivoting said movable jaw toward and away from said other jaw.

5. A device of the character described comprising a main frame adapted to be mounted on the boom of a lift truck, a second frame revolubly mounted on said main frame for rotation about a horizontal axis, a pair of opposed jaws mounted on said second frame, one of said jaws being fixed to said second frame and the other jaw being pivotal toward and away from said fixed jaw, and hydraulic means for pivoting said second frame about said horizontal axis and for pivoting said pivotal jaw toward and away from said fixed jaw.

6. A device of the character described comprising a main frame adapted to be mounted on the boom of a lift truck, a second frame revolubly mounted on said main frame for rotation about a horizontal axis, a pair of inner jaws arranged in back-to-back relationship and fixed with respect to said inner frame, a complemental pair of outer jaws, each pivotably mounted upon said second frame for pivotal movement toward and away from the companion fixed jaw, and hydraulic means for pivoting said second frame about said horizontal axis and for pivoting said pivotal jaw toward and away from said fixed jaw.

7. A device of the character described comprising a main frame adapted to be mounted on the boom of a lift truck, a second frame revolubly mounted on said main frame for rotation about a horizontal axis, a pair of fixed jaws fixed to said second frame, a pair of movable jaws, a lever for each said movable jaw, each said lever being pivotally supported upon said second frame and being operable to pivot its movable jaw toward and away from the companion fixed jaw, and hydraulic means for pivoting said second frame about said horizontal axis and for pivoting said levers and movable jaws toward and away from said fixed jaws.

8. A device of the character described compris-

ing a main frame adapted to be mounted on the boom of a lift truck, a second frame revolubly mounted on said main frame for rotation about a horizontal axis, a lever pivotally supported by said main frame and operable to pivot said second frame about said horizontal axis, hydraulic means for actuating said lever, and means interconnecting said hydraulic means and lever, such means being adjustable so as to actuate said lever relatively rapidly or relatively slowly, a pair of fixed jaws fixed to said second frame and a complemental pair of movable jaws pivotably supported upon said second frame, and hydraulic means for pivoting said movable jaws toward and away from said fixed jaws.

9. A device of the character described comprising a main frame adapted to be mounted on the boom of a lift truck, a second frame revolubly mounted on said main frame for rotation about a horizontal axis, a lever pivotally supported by said main frame and operable to pivot said second frame about said horizontal axis, hydraulic means for actuating said lever, means interconnecting said hydraulic means and lever, such means being adjustable to vary the distance between the point of connection and the fulcrum of said lever, a pair of fixed jaws fixed to said second frame, a complemental pair of movable jaws pivotably supported upon said frame for pivotal movement toward and away from the fixed jaws, a lever for each movable jaw, each said lever being pivotally supported upon said second frame and operable to pivot its movable jaw toward and away from the companion fixed jaw, and hydraulic means for actuating said levers.
